UNITED STATES PATENT OFFICE.

GREGGAR SMEDAL, OF LA CROSSE, WISCONSIN.

TYPE-WRITER ATTACHMENT.

1,196,164.

Specification of Letters Patent. Patented Aug. 29, 1916.

Application filed November 6, 1915. Serial No. 60,027.

To all whom it may concern:

Be it known that I, GREGGAR SMEDAL, a citizen of the United States, residing at La Crosse, in the county of La Crosse and State of Wisconsin, have invented certain new and useful Improvements in Type-Writer Attachments, of which the following is a specification, reference being had to the accompanying drawings.

10 This invention relates to certain new and useful improvements in typewriter attachments of the character shown and described in Patent No. 1,149,792, issued to me August 10, 1915.

15 My patented invention above referred to, comprehends means for supporting a plurality of paper rolls and a carbon roll with respect to the carriage of a typewriter for movement therewith, whereby duplicate copies may be made. In practice, I have 20 found it quite a difficult matter, in the use of this patented attachment, to tear off or sever the original and duplicate sheets from the paper rolls without also tearing the 25 carbon sheet, and it is the primary purpose of the invention forming the subject-matter of the present application, to eliminate this difficulty and supply a simple and effective means whereby the convenience and serviceability of the attachment in actual use, is 30 materially increased.

In the attainment of the desideratum above referred to, the present invention, in its broad aspect, involves the provision of 35 means whereby, when the writing is completed, the carbon sheet may be rewound upon its roller so that the original and duplicate copies may be cut or torn off from the paper rolls, and means whereby the complete withdrawal of the carbon sheet from beneath the platen is facilitated so that it is unnecessary to manually manipulate the carbon sheet in order to properly dispose the same between the paper sheets and beneath 40 the typewriter platen, in the subsequent operation of the same.

Considered in its more specific aspect, my invention contemplates the provision of a rewinding spring for the carbon roll, to 45 gether with a positive stop device to limit the rewinding of the carbon sheet upon the roll, and means whereby the tension of the spring may be easily and quickly changed when it becomes necessary to tear off a portion of the used carbon sheet so that when 50 the machine is again operated and the sheet

pulled beneath the platen, the spring will be automatically tensioned to rewind the carbon sheet for the desired distance.

With the above and other objects in view, 60 my invention consists in the novel features of construction, combination and arrangement of parts to be hereinafter more fully described, claimed and illustrated in the accompanying drawings, in which.

65

Figure 1 is a perspective view illustrating a manifolding attachment for typewriters such as that disclosed in my prior patent above referred to, and showing the preferred embodiment of the present invention applied to the carbon roller; Fig. 2 is a side elevation of a portion of the typewriting machine, showing the paper and carbon sheets extending beneath the platen and the position to which the carbon sheet has been 70 withdrawn beneath the platen after rewinding upon the carbon roller; Fig. 3 is an enlarged diametrical section through the rewinding device for the carbon sheet; Fig. 4 is a section taken on the line 4-4 of Fig. 3; 75 Fig. 5 is a perspective view of the latch arm for the spring case; Fig. 6 is a fragmentary perspective view of the carbon roller showing a slightly modified form of the invention; and Fig. 7 is a longitudinal sectional view 80 of this modified construction.

Referring in detail to the drawings and more particularly to Figs. 1 to 5 thereof, the numeral 5 indicates generally the paper and carbon roll carriage or support which is 90 mounted to travel with the movable carriage and platen of a typewriting machine, upon a suitable track indicated at 6. As the particular construction and mounting of the paper roll carriage and the track structure 95 is fully set forth in my issued Patent No. 1,149,792, the same will not be further described in detail. It will suffice to state that the traveling carriage or support includes spaced, forwardly projecting brackets 100 7 in which stub shafts or trunnions 9 on the opposite ends of the carbon roller 8, are rotatably mounted. One of these roller shafts 9 extends loosely through a peripherally grooved collar 11 formed upon one side of a 105 circular spring case 16, and the groove in this collar receives one of the supporting brackets 7. It is thus apparent that the spring case may be rotated with respect to the carbon roller, and vice versa. Within 110 the case 16, a spiral spring 12 is housed, one end of said spring being fixed to the wall of

the case by a pin 13. The other end of this spiral spring is provided with an opening for engagement over a lug 14 projecting radially from a sleeve 14' on the roller shaft 9 which extends through the case 10. The wall of the case 10 which is opposed to the roller supporting bracket, is provided with a circular series of openings 15 which are arranged in spaced relation. To the roller bracket 7, one end of a resilient latch plate 16 is fixed. This plate has an intermediate curved section in which spaced, laterally projecting studs 17 are fixed, and these studs are adapted to project through adjacent openings 15 in the wall of the case 10, thereby holding said case against rotary movement upon the shaft of the roller 8. The other or free end of the latch plate 16 projects forwardly beyond the edge of the case 10 so that it may be conveniently manipulated. 18 designates a face plate to cover the outer open side of the spring case 10, said plate being formed with a central, outwardly projecting hub or extension 19 having a peripherally milled head 20. This head has a rectangular longitudinal opening or bore therein which coincides with a cylindrical bore in the hub extension and body of the face plate 18, and said rectangular bore or opening is adapted to receive the square or rectangular extremity of the roller shaft indicated at 21. The end of the shaft is bored and threaded to receive the shank of a retaining screw 22, whereby the face plate 18 is secured upon the open side of the spring case 10. The plate 18 has a spiral groove 23 formed in its outer face, one end of said groove terminating adjacent to the periphery of the face plate and the other end thereof contiguous to the central hub extension on the plate. A lug or shoulder 24 is formed on the face of said plate in close proximity to the outer terminal of said groove. A stop finger 25 has a laterally projecting pin 26 fixed in one end thereof which is mounted to rotate in spaced ears 27 projecting from the periphery of the case 10. This finger has a laterally projecting spur or lug 28 formed thereon adjacent its free end, said lug being adapted for engagement in the spiral groove 23 provided in the face of the plate 17.

Attention is now directed to Fig. 2 of the drawings, wherein I have shown the attachment in connection with the platen of a typewriter. The platen, indicated at P, is equipped with the usual ratchet mechanism, whereby a step-by-step rotary movement is imparted to the same in the operation of the machine.

In the operation of my manifolding attachment, the paper from the upper and lower paper rolls and also the carbon strip or sheet from the roll 8, is drawn downwardly and engaged beneath the platen in

the usual manner, said platen being rotated until the sheets are disposed in the desired position. The typewriter is now operated in the usual manner and, as the writing proceeds, the original copy, the intermediate carbon sheet and the duplicate copy are moved together in such turning movement of the platen. Now it is obvious that, as the carbon sheet is thus pulled from the roller, the tension of the spring 12 is gradually increased. When it is desired to cut off or sever the original and duplicate copies, the pressure upon the paper and carbon sheets is released, and the spring 12 immediately acts to rewind the carbon sheet upon the roller 8, drawing said sheet upwardly between the two paper sheets until the free end edge of said carbon sheet is disposed approximately immediately beneath the platen. In this rewinding of the carbon sheet, it will be understood, from reference to Figs. 1 and 2 of the drawings, that the spring case 10 is held stationary while the face plate 18, fixed upon the end of the roller shaft, rotates with said roller. Now, as the lug 28 on the finger 25 is engaged in the spiral groove in the face of the plate 18, said finger gradually moves outwardly toward the periphery of the plate as the latter rotates, until the shoulder 24 on said plate engages against the lug 28 on the stop finger, thus stopping the further unwinding of the spring 12, and the rewinding of the carbon sheet. By thus limiting the movement of the carbon sheet under the action of the spring, the proper disposal of its free end beneath the platen is assured so that it will not be necessary to manually manipulate or adjust said sheet beneath the platen in the subsequent operation of the machine. As the carbon sheet is again unwound from the roller, the free end of stop finger will move inwardly from the outer edge of the plate 18 toward its center, as will be readily understood. When it is necessary to tear off the part of the carbon sheet which has been completely used up, in order that the spring will not be so tightly wound when the carbon is withdrawn from the roll as to preclude the continued unwinding of the carbon sheet in the next operation of the machine, I have provided the means for decreasing the tension of the spring 12. This means consists in the resilient latch plate 16. By forcing the free end of this plate 16 inwardly, the studs 15 thereon may be withdrawn from the openings in the wall of the case 10 so that said case may turn upon the end of the roller shaft. Thus, after the used section of the carbon sheet is torn off and the sheet again pulled downwardly and disposed beneath the platen, the spring 12 will be properly tensioned in the operation of the machine so that when the platen is released, the carbon will be rewound on the 125

roller for the desired distance to insure the proper disposal of the end of the sheet with respect to the platen.

If desired, a relatively stationary knife or cutting means for the paper sheets, such as that disclosed in my prior patent, may be provided.

Figs. 6 and 7 of the drawings, I have illustrated a slightly modified form of the invention, wherein the carbon roller, indicated at 8', is in the form of the ordinary shade roller, having a fixed trunnion on one end and a non-rotatable rod or shaft 9' in its other end. One end of the winding 10 spring 30, housed within the roller, is connected to this rod. In this modified construction, one end of the roller 8' has a metal sleeve 31 fitted and suitably fixed thereon, and a relatively large circular metal 15 disk 32 is formed upon one end of said sleeve. The sleeve 31 is provided upon its periphery with a spiral groove 33 terminating at its ends in the stop shoulders 34. The outer face of the disk 32 is provided 20 with a similar spiral groove 35 at the opposite ends of which the shoulders 36 are formed. Upon one of the roller supporting brackets 7, a stop finger or arm 37 is pivoted at one of its ends, as at 38, the other 25 end of said finger being angularly disposed and engaged in the spiral groove 35 of the disk 32. A pin 39 is also rotatably mounted in the bracket 7 and, upon one end thereof, a coil spring 40 is disposed, one terminal of 30 the spring being fixed to said pin and the other terminal thereof being engaged with the edge of the roller bracket 7. Upon the other or inwardly projecting portion of this pin 39, a finger 41 is pivoted, the free end 35 of said finger being engaged in the spiral groove 34 on the periphery of the sleeve 32. The spring 40 yieldingly holds the free end of the finger 41 in the spiral groove, as will be readily understood. Thus, it will be seen 40 that there is double provision against the entire rewinding of the carbon sheet upon the roller 8', and if one of the stop fingers should accidentally become disengaged from the spiral groove, the other of said fingers 45 will remain as an effective limiting stop to the rotation of the roller. However, it is manifest that, if desired, either one of these stop devices may be dispensed with, and only a single stop employed.

50 From the foregoing description, taken in connection with the accompanying drawings, it will be appreciated that I have devised a very essential and desirable adjunct to my patented invention. By the provision 55 thereof, the operator may readily tear or cut off the typewritten sheet from the paper rolls without in any way mutilating or tearing the carbon sheet, as said sheet is withdrawn and rewound upon the carbon roller 60 immediately upon the release of the paper.

The soiling of the hands in the manual manipulation of the carbon sheet is also avoided, as the limiting or stop means for the carbon roller will positively operate to prevent the entire withdrawal of the carbon 70 sheet from beneath the platen so that it is only necessary for the operator to re-position the two paper sheets on the opposite sides of the carbon sheet and under the platen when the operation of the machine 75 may be continued. The addition of this automatic rewinding device for the carbon or other duplicating sheet does not greatly complicate the construction of the original invention as shown in my prior patent, or 80 materially add to the manufacturing cost thereof. It is also possible, in view of the mounting and arrangement of the several parts, to utilize a plurality of interchangeable spring casings and different sizes of 85 spiral springs so that the carbon sheet may be withdrawn to a greater or less extent, as desired, in accordance with the length of the written sheets, before the spring is completely unwound and the stop device comes 90 into operation. Thus, the invention is capable of adaptation at relatively small expense for use in connection with the manifolding attachment when employed in the preparation of way bills, credit or account statements, and the like.

While I have above disclosed what I believe to be the present preferred embodiments of the device, it is to be understood that the same is susceptible of considerable modification therein and I, therefore, reserve the privilege of adopting all such legitimate changes as may be fairly embodied within the spirit and scope of the invention 95 as claimed.

Having thus fully described my invention, what I desire to claim and secure by Letters Patent is:—

1. The combination with the platen of a typewriting machine, of paper and carbon 110 rollers supported contiguous to the platen whereby the paper and carbon sheets may be engaged under the platen, means automatically operating upon the release of the paper to reverse the rotation of the carbon 115 roller and rewind the carbon sheet thereon, a movable stop element, means fixed on the roller shaft co-acting with the stop element to actuate the same, said means carrying a stop shoulder, said element being shifted 120 into the path of movement of said shoulder in the rewinding of the carbon sheet to stop the reverse rotation of the roller, whereby the position of the free end of the carbon sheet with respect to the platen may be 125 predetermined.

2. The combination with the platen of a typewriting machine, of paper and carbon rollers supported contiguous to the platen whereby the paper and carbon sheets may 130

- be engaged under the platen, means automatically operating upon the release of the paper to reverse the rotation of the carbon roller and rewind the carbon sheet thereon, a movable stop element, a disk fixed on the roller shaft and provided with a shoulder, said disk being further provided with means engaged by the stop element whereby said element is shifted into the path of movement of the shoulder to stop the re-winding of the carbon sheet.
3. The combination with the platen of a typewriting machine, of paper and carbon rollers supported contiguous to the platen whereby the paper and carbon sheets may be engaged under the platen, means automatically operating upon the release of the paper to reverse the rotation of the carbon roller and rewind the carbon sheet thereon, a movable stop element, a disk fixed on the roller shaft and provided with a shoulder, said disk being provided with a spiral groove co-acting with said stop element and having means at the end of said groove for engagement with said element to limit the re-winding of the carbon sheet.
4. The combination with the platen of a typewriting machine, of paper and carbon rollers supported contiguous to the platen whereby the paper and carbon sheets may be engaged under the platen, means automatically operating upon the release of the paper to reverse the rotation of the carbon roller and rewind the carbon sheet thereon, a pivoted stop finger provided with a lug, and a disk fixed upon the roller shaft having a spiral groove in its face in which said lug is engaged, whereby the finger is shifted in the rotation of the carbon roller, said disk being also provided with a shoulder in the path of movement of which said lug is

disposed in the rewinding of the carbon sheet.

5. The combination with the platen of a typewriting machine, of paper and carbon rollers supported contiguous to said platen for the engagement of the paper and carbon sheets therewith, a spring case loosely mounted upon the shaft of the carbon roller and open upon one side, a cover plate for the open side of said case fixed upon the roller shaft, a spring within said case to rewind the carbon sheet upon the roller, a fixed resilient latch member having means for adjustable engagement with the loosely mounted case, whereby said case is held against rotation with respect to the roller shaft, and means co-operating with means on the cover plate for the open side of said case to limit the rewinding of the carbon sheet upon said roller under the action of said spring.

6. The combination with a roller and a paper sheet wound thereon, of a spring connected to said roller and placed under tension when the paper sheet is drawn therefrom to rewind the sheet upon said roller when the sheet is released, a disk fixed upon the roller shaft and having a spiral groove in its face and a shoulder at the outer terminal of said groove, and a movable element operating in said groove and automatically shifted in the rewinding rotation of the roller into the path of movement of said shoulder to positively limit the rewinding of the paper sheet.

In testimony whereof I hereunto affix my signature in the presence of two witnesses.

GREGGAR SMEDAL.
